CARVING FORK OR THE LIKE

Clayton A. Laughlin, Minneapolis, Minn., assignor to Arthur Salm Inc., Chicago, Ill., a corporation of Illinois

Filed May 26, 1969, Ser. No. 17,334

Term of patent 14 years

Int. Cl. D7—03

U.S. Cl. D44—29

FIG. 1 is a side elevational view of a carving fork showing my new design;

FIG. 2 is a left end elevational view;

FIG. 3 is a right end elevational view;

FIG. 4 is a top plan view; and

FIG. 5 is a bottom plan view.

I claim:

The ornamental design for a carving fork or the like, substantially as shown.
